UNITED STATES PATENT OFFICE.

WILLIAM S. WESTON, OF DALLAS, TEXAS.

ANTICREEPER FOR RAILWAY RAILS.

Application filed July 3, 1922. Serial No. 572,477.

To all whom it may concern:

Be it known that I, WILLIAM S. WESTON, a citizen of the United States, residing in the city of Dallas, county of Dallas, and State of Texas, have invented certain new and useful Improvements in Anticreepers for Railway Rails, of which the following is a full, clear, and exact description.

My invention relates to anticreepers for railway rails of the type having a transverse bar beneath the rail provided with shoulders adapted to bear against the opposite rail base edges, and which, in installation and functional operation, is slightly rotated in a plane parallel to the bottom surface of the rail base in a manner to bring the shoulders to their bearings and thereby to establish a lever grip on the rail. My invention relates more particularly to a V form spring clamp type similar in many respects to that illustrated in U. S. Letters Patent No. 1,120,258 granted to me Dec. 8th, 1914, and No. 1,257,566 granted to me Feb. 26th, 1918, in which three primary points of bearing on the rail are provided for and in which the manufactured form is smaller than the base of the rail on which it is to be sprung in the process of installation.

My present invention is embodied in a spring clamp V form made in two pieces, and my object is to provide in combination, a transverse bar member with unyielding shoulders for bearing against the opposite rail base edges so placed in position as to have a lever grip on the rail operating in a horizontal plane, and a separate longitudinal member adapted to be sprung into place to hold the transverse bar in operative position and to transmit the tie reaction thereto. The novel construction whereby I attain this object and other novel features of improvement are hereinafter described and clearly illustrated in the accompanying drawings which form a part of these specifications and are particularly pointed out in the claims.

In the drawings Fig. 1 is a side elevation of a rail showing the anticreeper in position against a tie. Fig. 2 is an elevation transverse to the rail as seen from the left of Fig. 1, but with the tie omitted. Fig. 3 is a plan or downward view with the rail and tie shown in full lines. Fig. 4 is a plan view partly in section on the line 4-4 of Fig. 1, the rail base outline being

indicated by dotted lines. Figs. 5 and 6 are plan views to illustrate initial installation positions of the parts of the device in the process of bringing it to the final position shown in the first four figures. Fig. 7 is a plan view illustrating the shape of the device as manufactured and the two members assembled off the rail, and shows that the seating space is narrower than the rail base on which it is to be sprung when installed. The same letters and numerals of reference indicate the same parts in the several views.

Described in detail the device consists of a transverse bar member B with shoulders 1 and 2 bearing against opposite edges of the rail base and a longitudinal member C adapted to be snapped into position on the bar and the rail and have a point 3 for concentrated bearing against one rail base edge. The three points of bearing 1, 2, and 3 constitute a rail seating space narrower than the rail base if, before installation on the rail, the two members B and C are assembled in their manufactured shape as shown in Fig. 7. In the process of installation this space is expanded by the spring action of a part 4 of the member C, and the resilience of this part after installation provides for a permanent initial grip between the anticreeper and the rail. In respect to the points of bearing 1, 2, and 3, and the resilient action just described it will be noted that my present invention embodies a fundamental feature of the devices described in my prior patents referred to.

The member C is made of spring steel or other material of high elastic limit. It is provided with a top flange 5 overlapping the base flange of the rail R, and a bottom flange 6 passing beneath the bar B. It is sleeved over the end of the bar B which in installation is caused to pass through a hole 7 partly formed when the part 4 in the shape of a tongue is punched from the vertical face into a position under the rail with its end bearing against the back of the bar B. The forward edge 8 of this hole is designed to take a seat inside of a shoulder 9 on the forward side of the bar B. The distance between the edge 8 and the end of the tongue 4 is expanded at installation, and the resilient quality of the shape tends to rotate the member C from the position of Fig. 4 to that of Fig. 7.

The resilient action of the tongue 4 holds the edge 8 close in behind the shoulder 9 and the interlocking relation of the two members is such that member C is held 5 clear of the rail base edge except at the forward end at the point 3, as shown in Fig. 4.

To prevent the bar B from dropping away from the rail the end with shoulder 1 on the opposite side of the rail from member C is provided with a lip 10 slightly over-hanging the base flange. The end with shoulder 2 is prevented from dropping away by the bottom flange 6 of member C. A cross section of member C taken adjacent the edge 8 is indicated by the dotted outline in Fig. 2.

At installation the bar B is first passed beneath the rail substantially at right angles thereto as shown in Fig. 5 so that the lip 10 can be hooked over the base flange and the body of the bar brought up against the bottom of the rail. The bar is then rotated in the direction indicated by the circular arrow in Fig. 6, a small amount to an angle with the rail something less than ninety degrees, until the shoulders 1 and 2 take a firm unyielding bearing against opposite edges of the rail base. The member C is then placed by hand on the end of the bar in the position shown in Fig. 6 with the forward end adjacent the point 3 resting against the rail base edge. Hammer blows are then applied to member C, first near the center and in the direction indicated by the arrow 12, and finally as indicated by the arrow 13, until it takes the position of Fig. 4. In this process the tongue 4 is sprung something beyond the amount indicated by the dotted outline in Fig. 6 until the edge 8 clears and can drop in behind the side shoulder 9 of the bar. The tongue then recovers part of the distance through which it was sprung and operates to hold the edge 8 in its seat behind the shoulder 9. It will be observed that the reaction between the end of the tongue 4 and the edge 8 tends to rotate the bar B still further in the direction indicated by the circular arrow 11, and thereby maintains the lever grip on the rail with the shoulders 1 and 2 acting as the fulcrums. The reaction of the tongue is utilized also to take up any effect of looseness that might arise from any slight variation from the normal width of the rail section on which the anticreeper is to be used.

The forward end of the member C adapted to bear against and receive the reaction thrust of the tie T is preferably provided with a flange 14 to stiffen the shape and increase the tie abutting surface. To prevent vertical movement of this end of the member, due to friction against the tie as the rail rises and lowers under the passing load, the forward portion of the vertical face is 65 pressed inward and under the rail base at

15. By this construction a short flange 15 bracing jaw 16 reenforced by the flange 14 is formed on the forward end of member C. By this construction also the center line of the tie reaction thrust is brought slightly 70 beneath the rail base edge as indicated by the arrow 17 in Fig. 4.

In functional operation the tie reaction is transmitted by member C to the bar B through the seat of the edge 8 behind the shoulder 9 and thence to the rail through the medium of the lever grip of the bar on the rail already established at installation, as described. That this is a genuine lever grip is clear from the fact that the tie reaction 80 thrust is transmitted to the bar just inside the shoulder 9 and at a point relatively outside the two fulcrums 1 and 2, rather than at any point between these fulcrums. Because of its length and shape the member C 85 in itself will have little or no grip on the rail through the establishment of a lever grip acting in a vertical plane, and a high percentage of the total reaction thrust will be transmitted to the rail through the bar B. 90 The bar and its shoulders therefore are made as heavy and unyielding as may be necessary.

With the center line of the tie reaction lying within the shoulder 9 for normal operation parallel to the rail it is to be noted that there will be no tendency to open up the angle of the V formed by the lines of connection between the three bearings 1, 2, and 3. In operation if the shoulders at 1 and 2 become slightly embedded in the rail base edges the bar is rotated still further in the direction of the circular arrow 11, reducing the angle of the V. This reduced angle will be maintained by a further recovery of the 105 resilient tongue 4. It is especially to be noted that the functional operation does not add to the strain in the tongue 4. In the action just described the strain is gradually relieved as the device becomes embedded to 110 its seats.

To set the anticreeper close up to the tie hammer blows may be applied to the end of the bar B on the side carrying the longitudinal member and in a direction toward 115 the tie as indicated by the arrow 18, Fig. 4. To move it away from the tie hammer blows may be applied to the other end in the direction indicated by the arrow 19. To remove the anticreeper from the rail it is first 120 backed away from the tie a slight amount. Then a pinch bar or other tool is used to hold the end of the bar B adjacent the shoulder, but not too close to the edge 8 of member C, and a sharp hammer blow applied to 125 member C as indicated by the arrow 20. That will cause the edge 8 to snap out from behind the shoulder 9. If through frequent installation and removal the distance between the end of the tongue 4 and the edge 130

8 becomes too great to be effective it may be closed up easily with a hammer.

A feature of importance attained by the novel construction of my two piece anti-creeper is the provision against the loosening of the device from the rail should the rail creep backward in the opposite direction from that indicated by the arrow 21 in Fig.

1. In case the anticreeper is embedded in 10 frozen ballast and the rail moves backward the member C acts on the bar B with the same result as from the hammer blow applied at point 18, and the device is retained in its position against the tie. This action 15 illustrates the fact that the device, when held to the tie by the ballast or by any means acting similarly on the member C, as for example another tie placed against the other end opposite the tie T, the device will perform the full function of a lever grip mechanism, or as sometimes called a shackle mechanism, holding the thing gripped against movement in one direction and freeing it for movement in the opposite direction.

25 Changes may be made in the exact form of either or both members without changing the method and principle of installation and operation. I therefore claim broadly, as well as in combination with other features,

30 a two piece anticreeper for railway rails comprising a transverse bar member with unyielding shoulders adapted to bear directly against the opposite rail base edges and have a lever grip on the rail base; and a tie 35 abutting member mounted longitudinally to the rail on one base flange in a spring retained bearing between it and the transverse member, and adapted to transmit the tie reaction thrust through the transverse member 40 and the lever grip to the rail; the reaction in said spring retained bearing between the members operating to establish and maintain said lever grip.

45 What I claim as new and desire to secure by Letters Patent is:—

1. An anticreeper for railway rails comprising a transverse member having shoulders for bearing against the opposite rail base edges when placed beneath the rail, and 50 adapted to have a lever grip on the rail base; and a longitudinal tie-abutting member overlapping one rail base flange and interlocked with one end of the transverse member; the longitudinal member having a point 55 of bearing against the edge of said flange when sprung into interlocked engagement with the transverse member, and adapted thereby to maintain the said lever grip of said transverse member.

60 2. An anticreeper for railway rails comprising a transverse bar member having shoulders for bearing against the opposite rail base edges when placed beneath the rail, and adapted to have a lever grip on the rail 65 base; and a longitudinal tie-abutting mem-

ber supported by one rail base flange and adapted to be sleeved over and sprung into interlocked engagement with one end of said bar member; the interlocked engagement operating to rotate the transverse member in a horizontal plane and thereby maintain said lever grip.

3. An anticreeper for railway rails comprising two members interlocked in spring relation one with the other; one of said members having unyielding shoulders for bearing against the opposite rail base edges when placed transversely beneath the rail and adapted to have a lever grip on the rail base; and the other of said members placed longitudinally with the rail, having a tie abutting portion, a flange portion overlapping one rail base flange, and a single point of bearing against the edge of said base flange; the spring relation between said single point of bearing and said unyielding shoulders operating to establish and maintain said lever grip.

4. An anticreeper for railway rails comprising two members interlocked in spring relation one with the other; one of said members having unyielding shoulders for bearing against the opposite rail base edges when placed transversely beneath the rail and adapted to have a lever grip on the rail base; and the other of said members placed longitudinally with the rail, having a tie abutting portion, a flange portion overlapping one rail base flange, and a single point of bearing against the edge of said base flange; the said single point of bearing forming in spring relation with said unyielding shoulders a rail base seating space that is expanded in the process of installation to the width of the rail base on which the anticreeper is to be seated.

5. A two part anticreeper for railway rails having three points of transverse bearing against the edges of the rail base; comprising a first part carrying two of said points of bearing in unyielding relative relation on opposite edges of the rail base; and a second part carrying the third point of bearing against one edge of the rail base mounted in spring engagement with the first part, whereby said first part with its two points of bearing acting as the fulcrums on opposite edges is caused to grip the rail base in a lever grip.

6. A two part anticreeper for railway rails having three points of transverse bearing against the edges of the rail base; comprising a first part carrying two of said points of bearing in unyielding relative relation on opposite edges of the rail base; and a second part carrying the third point of bearing against one edge of the rail base mounted in spring engagement with the first part, whereby said first part with its two points of bearing acting as the fulcrums on

opposite edges is caused to grip the rail base in a lever grip; and means for holding the anticreeper against the tie whereby the said lever grip, operating to prevent movement of the rail in one direction, permits the free movement of the rail therethrough in the opposite direction.

7. A two piece anticreeper for railway rails comprising a transverse bar member with unyielding shoulders adapted to bear directly against the opposite rail base edges and have a lever grip on the rail base; and a tie abutting member mounted longitudinally to the rail on one base flange in a spring retained bearing between it and the transverse member, and adapted to transmit the tie reaction thrust through the transverse member and the lever grip to the rail; the reaction in said spring retained bearing between the members operating to establish and maintain said lever grip.

8. A two-piece anticreeper for railway rails comprising a transverse bar having rigid portions for engaging the opposite rail base flanges and adapted to have a lever grip on the rail base when in operative position,

and a tie-abutting member adapted to hold said transverse bar in operative position and to transmit the tie reaction thrust to the rail through said bar by means of such lever grip.

9. A two-piece anticreeper for railway rails adapted to be mounted on the rail base so as to abut against a cross tie in functional operation, and comprising a transverse bar having rigid shoulders arranged to grip the opposite edges of the rail base when rotated in a horizontal direction into operative position, and a second member arranged to be supported by one rail base flange and adapted, by an interlocked spring relation with said transverse bar to hold the latter in such operative position.

10. A two-piece rail anchor comprising a transverse bar arranged to extend beneath the rail and engage one of the rail base flanges and a tie abutting member arranged to engage the other rail base flange and adapted to be sprung into interlocking engagement with said bar.

WILLIAM S. WESTON.
